FOREIGN PATENT DOCUMENTS

EM 002467605-0001 5/2014

Primary Examiner — Elizabeth A. Albert(74) *Attorney, Agent, or Firm* — Global IP Counselors, LLP(57) **CLAIM**

The ornamental design for a electric polisher, as shown and described.

DESCRIPTION

FIG. 1 is a front perspective view of an electric polisher showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is another front perspective view thereof.

The broken lines are included for the purpose of showing features that form no part of the claimed design.

1 Claim, 8 Drawing Sheets(56)
